HEAT DISSIPATING SYSTEM FOR
BEARINGSThomas J. Bay and Morris R. Machol,
Washington, D. C.

Application May 18, 1942, Serial No. 443,484

4 Claims. (Cl. 308—77)

This invention relates to bearings and it has a particular relation to cooling means therefor.

In most bearings there is a space or air gap, small though it may be, between the babbitt metal and the metal of the bearing housing which presents an effective barrier to the transfer of heat from the former to the latter. This impediment to the passage of heat is particularly noticeable in railway car bearings in which even though the babbitt metal is cast in a bronze backing member an air gap exists between this member and the steel bearing wedge and also between the wedge and the housing or journal box. Inasmuch as a large proportion of the heat generated by friction between the journal and the bearing and between the journal and the waste must be dissipated by this route over-heating and hot boxes are a frequent occurrence.

The principal object of the present invention is to assist in the transfer of heat from a bearing by short circuiting the air gaps above described by means of one or more conductors of relatively high thermal conductivity thermally bonded at one end to the babbitt metal of the bearing or to the backing member if the babbitt is cast therein, and also thermally bonded at its other end to the housing or other metallic member located remote thereto and capable of readily dissipating heat transferred thereto. This member may, in the case of railway car bearings, be a portion of the journal box located in the air stream, or in an electric motor, this member may be the motor casing. In certain other installations the heat may be transferred through such a conductor to a portion of a ship or building located a considerable distance from the bearing and having the necessary heat dissipating characteristics.

With these and other objects in view, as well as other advantages that may be incident to the use of the improvements, the invention consists in the parts and combinations thereof herein-after set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawing means for carrying the invention into practical use, without limiting the improvements in their useful application to the particular construction, which, for the purpose of explanation, have been made the subject of illustration.

In the accompanying drawing:

Fig. 1 is a perspective view of a railway car bearing showing a heat conductor connected at one end with the bearing back and at its other end with the journal box at a point located in the air flow;

Fig. 2 is a fragmentary transverse sectional view on a larger scale showing the heat conductor thermally bonded at its inner end to the babbitt metal;

10 Fig. 3 is a similar view showing the inner end of the heat conductor thermally bonded to the bearing back;

15 Fig. 4 is an enlarged fragmentary sectional view showing one method of thermally bonding the outer end of the heat conductor to the bearing housing or other heat dissipating or absorbing element; and

Fig. 5 is a view partly in elevation and partly in section of a bearing of conventional type where-
20 in the inner end of the heat conductor is em-
bedded in the babbitt metal and its other end
thermally bonded to a heat absorbing or dissipat-
ing element located remote to the bearing.

Referring to the drawing, and particularly to
25 Fig. 1 thereof, a railway car bearing is shown as comprising a bearing housing or journal box 10 equipped with the usual dust plate 11 which surrounds the axle or shaft 12 adjacent to the axle journal 13 and which functions as a heat dis-
sipating means. Supported by the journal 13 is a backing member 14 of bronze or bronze alloy to the inner face of which a shaft-engaging bush-
30 ing of babbitt 15 is thermally united by casting. This member is held in position by a steel wedge
35 16 which bears directly upon the journal box 10. It will be noted from an inspection of Figs. 2 and
3 that there is an air gap 17 between the backing
member 14 and the wedge 16 and also an air gap
18 between the wedge and the journal box 10.
40 In some instances there may also be an air gap
19 between the babbitt metal 15 and the backing
member 14. These air gaps, small as they are,
present a serious barrier to the transfer of heat
to the journal box for dissipation thereby.

45 According to the present invention, this diffi-
culty is overcome by short circuiting or by-pass-
ing the air gap or gaps by means of a member
20 having a high coefficient of thermal con-
ductivity and herein shown as consisting of a strand-
50 ed wire cable of copper or other suitable metal.
As illustrated in Fig. 2, the conductor 20 passes
through an opening 21 drilled in the backing
member 14 and its inner end is frayed and em-
bedded in the babbitt metal 15 to provide a
55 thermal bond therewith. In forming this type

of bond the separate strands of the conductor are pressed against the surface of the backing member 14, after which the babbitt metal is cast in position so as to embed the several strands of the conductor therein. It will be noted that in this method the strands of the conductor are located at a point remote to the journal engaging surface of the babbitt so as to allow for considerable wear before exposing or contacting the strands of the conductor. The outer end of the conductor 20 extends into an aperture 23 drilled in the journal box 10, part of which is located in the air stream and is thermally bonded therein by soldering, brazing or welding, as indicated at 24. In forming this connection the surface of the aperture 23 and the end of the conductor are tinned or otherwise suitably prepared, and the end of the conductor inserted in the aperture. The strands of the conductor are then spread into intimate contact with the wall of the aperture by a center punch or drift pin and a wedge 25 of solder then driven in the opening thus formed, as shown in Fig. 4. The conductor and surrounding area of the journal box is then heated in any suitable manner, such as by a blow torch, until the solder is melted and forms a thorough bond between the strands of the cable and the wall of the journal box.

In some installations it may be found to be more convenient and practical, particularly in replacement jobs, to thermally bond the inner end of the conductor 20 in a socket 26 drilled in the backing member 14, as shown in Fig. 3.

In Fig. 5 there is illustrated diagrammatically a conventional bearing in which a babbitt liner 28 is cast into dovetailed slots 29. In this form of the invention a stranded conductor 30 passes through an opening 31 in the bearing cap 32 and its inner end frayed and the several strands thereof tinned and bent into one of the adjacent slots after which the babbitt metal is cast in position so as to embed the strands of the conductor therein. Also, in this figure the conductor is shown as being thermally bonded, as at 33, to a heat dissipating metallic means or element 34 located at a point spaced from the bearing. This element may be the casing of an electric motor, the wall or roof of a building, or the hull or bulkhead of a ship according to the nature of the installation. Also, in some instances, the outer end of the conductor 30 may be secured to a separate water cooled device or it may be immersed in a cooling element.

From the foregoing it will be appreciated that a very effective means is provided for augmenting the cooling of a bearing and one that may be incorporated at little expense in a bearing

either initially or when it may become necessary to reline the bearing, or at any intermediate time.

It will be understood that the above description and accompanying drawing comprehend only the general and preferred embodiment of the invention and that various changes in construction, proportion and arrangement of the parts may be made within the scope of the appended claims without sacrificing any of the advantages of the invention.

The invention described herein may be manufactured and used by or for the Government of the United States of America for governmental purposes without the payment of any royalties thereon or therefor.

What is claimed is:

1. A bearing structure including a backing member, a bushing member thermally united with said backing member for frictional contact with a shaft, heat dissipating means spaced from said backing member, and a flexible cable having a relatively high coefficient of thermal conductivity arranged to bridge the air gap between said backing member and the spaced heat dissipating means and thermally bonded at one end to said heat dissipating means and at its other end to one of the thermally united members.

2. A bearing structure including a bearing housing, a backing member in said housing and having an air gap therebetween, a bushing member thermally united with said backing member for frictional contact with a shaft, and means having a relatively high coefficient of thermal conductivity arranged to bridge said air gap and thermally bonded at one end to said housing and at its other end to one of said thermally united members.

3. A bearing structure including a bearing housing, a backing member in said housing and having an air gap therebetween, a bushing member thermally united with said backing member for frictional contact with a shaft, and a flexible cable having a relatively high coefficient of thermal conductivity arranged to bridge said air gap thermally bonded at one end to said housing and at its other end to said bushing member.

4. A bearing structure including a bearing housing, a backing member in said housing and having an air gap therebetween, a bushing member thermally united with said backing member for frictional contact with a shaft, and a flexible cable having a relatively high coefficient of thermal conductivity arranged to bridge said air gap and thermally bonded at one end to said housing and at its other end to said backing member.
